M. J. HOSCH

HOG WATER FOUNTAIN

Filed Sept. 12. 1924

UNITED STATES PATENT OFFICE.

MATHIAS J. HOSCH, OF RANDOLPH, NEBRASKA.

HOG WATER FOUNTAIN.

Application filed September 12, 1924. Serial No. 737,367.

This invention is an improvement in hog water troughs, and it consists of the constructions, combinations and arrangements herein described and claimed.

5 An object of the invention is to provide a water trough or fountain to be used in hog pens, there being an arrangement of pans to hold mud, and an arrangement of valves to prevent mud from entering the float chamber.

10 Another object of the invention is to provide a hog water fountain from which the mud pan may be readily removed for cleaning.

15 Other objects and advantages will appear in the following specification, reference being had to the accompanying drawing in which

Figure 1 is a perspective view of the improved hog water fountain, the cover of the float chamber being omitted,

Figure 2 is a longitudinal section thereof, the float chamber cover being in place,

20 Figure 3 is a detail perspective view of one of the mud pans.

Figure 4 is a detail section on line 4—4 of Fig. 2.

In carrying out the invention provision is made of a frame generally designated 1 and 25 consisting of pairs of end and side slabs 2 and 3 which respectively are alike. These slabs are composed of any suitable material but are preferably made of cement, this material being regarded as more suitable for 30 the purpose than the majority of other materials. The slabs are fastened together by suitable means, for example bolts 4 which extend through from side to side and carry nuts 5 at the ends.

40 Each side slab has an upward extension 6. These are shorter than the slabs (Figs. 1 and 2) and the corners of the portions or surfaces of the slabs which merge with the extension are notched at 7 to receive the 45 flange of a binder on the cover 9. The cover is arranged to seat upon the upward extensions, and that portion of the binder 8 which extends below the cover thereby forming a flange, seats in the notches of the flange to 50 prevent displacement of the cover from that portion of the fountain known as the float chamber.

55 Situated in the top of the container 1 is a trough 10 which has end flanges 11 resting upon the upper edges of the end slabs 2 thereby sustaining the trough in position.

The adjacent upper and inner ends of the slabs 2 may be beveled at 12 (Fig. 2) to accommodate the correspondingly inclined ends of the trough. Partitions 13 and 14 60 extend upward beyond the upper edges of the trough until they substantially meet the upper surface of the extensions 6. The extended partitions therefore occupy places immediately behind the binder flange and make a very snug joint. The arrangement produces a good seat for the cover 9 and the overlapping arrangement of the flange 8 and partitions 13 and 14 produces a joint through which contaminating matter cannot enter 65 into the float chamber.

70 This float chamber is situated between the partitions 13 and 14, and is so characterized by the presence of a float 15 which is arranged to operate a valve 16 by which the flow of water is controlled. The float is directly carried by a lever 17 which is suitably suspended from a bracket 18. The lever 17 has a more or less loose connection with the valve lever 19 which is pivoted at 75 20 upon the casing of the valve in any suitable manner and is adapted to hold the valve 16 closed as long as the float 15 is up to a predetermined water level. Upon lowering of the float the resulting movement of the levers 17 and 19 permits the valve 16 to open, a spring 21 being provided for the purpose, so that water may enter at the conduit 22. This conduit may be a pipe, 80 hose or any other suitable conductor leading 85 to a source of water supply.

90 Each of the partitions 13 and 14 is slightly bulged at 23 to produce a housing, recess or chamber for the flap valves 24 which are slightly weighted at 25 thereby tending to 95 hold the valves down in position to cover the water openings 26. The valve chambers 23 are of substantially rectangular form, or of any other suitable form to properly contain the flap valves. Upon lowering of the 100 level of water in the end pan the valve 24 opens sufficiently to let more water through from the float chamber. But on the other hand the flap valve operates to prevent mud and other contaminating substances from 105 passing from the end pan into the float chamber.

110 The so-called end pans are defined by the partitions 13 and 14, in other words, the partitions produce end pans and the central float chamber. The end pans have false bottoms or mud pans 27 and 28 for the par-

ticular purpose of catching all sediment, (mud, etc.) and thereby facilitating cleaning the trough 10. Each mud pan has a bail 29 carrying a latch 30, each of which 5 is intended to be moved into engagement with a flange 31 running across the partitions a short distance below the upper edges. These flanges are situated sufficiently far down to come in substantial registration 10 with the bottoms of the notches 7, thereby producing continuations of the notches for the reception of the flanges at the ends of the cover. These flanges therefore assist in effecting the tight joint referred to above. 15 It is by means of the bails 29 that the mud pans are lifted out of the end water pans. The bails provide mountings for the latches, and upon moving the latches under the flanges 31 the mud pans are locked in place.

20 A suitable stove 32 keeps the water in the trough 10 in a liquid condition in the winter time. The stove is simply stood upon the ground inside of the container 1, one of the side slabs 3 having an opening 33 (Fig. 25 1) for the purpose of admitting the stove. A pair of brackets 34 are imbedded in this slab at the sides of the opening and a door 35 is set in place behind the brackets. The 30 sides of the door 35 have pairs of long and short bevels 36 and 37, it being the high points or apex of the bevels that engage the brackets and so hold the door in place. When the door is in the particular position shown in Figure 1, the opening 33 will be 35 closed entirely with the exception of such draft as may enter at a vent 38. The door may be reversed in position, and there will then be a decided space left between the then lower edge of the door and the bottom of 40 the opening 33. The door has a projection or handle 39 by means of which the door is slid into and out of position.

The operation may be briefly reviewed to 45 advantage. It has been pointed out that the notches 7 of the upper extensions 6 coincide with the corners formed by the partitions 13 and 14 and the flanges 31 carried thereby. The binder flange of the cover 9 is intended to occupy the notches 7 and corner flanges 31 when seated upon the upward 50 extensions, thus providing a good joint all around tending to exclude foreign matter from the float chamber of the fountain.

This float chamber is formed by the partitions 13 and 14 and these partitions also 55 define the end water pans of the trough 10. The rising and falling of the float 15 controls the valve 16 in such a manner that water is always supplied to the float chamber at such level as may be determined by the particular adjustment of the float 15. The flap valve 24 controls the passage of water from the float chamber to the end water pans. Hogs, in drinking from the 60 end water pans, are likely to pollute the

water more or less. The foreign matter introduced into the end water pans at the time of drinking settles into the so-called mud pans 27 and 28.

These mud pans are capable of again being taken out by merely undoing the latches 30 from engagement with the flanges 31 and lifting the mud pans out by the bails 29. The flap valves 24, mentioned before, are intended to prevent a back flow of water 75 from the end water pans into the float chamber. The source of supply of the end water pans is thus kept clean. It is to be noted that the flap valves are seated in 80 chambers formed by producing bulges in the partitions 13 and 14. There is room enough between the bottom of the bulge and the adjacent upwardly extending part of the mud pan bail to permit the requisite movement of the flap valves.

85 Reference is made to Figure 4 which is a detail section of one of the upward extensions 6 of the side slabs 3. Each of the extensions has a slight offset 41 on the inside producing a place where the continuation 42 of the flange 11 of the trough 10 may rest when the trough is in position. The flange 11—42 is continuous around the trough, and when the trough is seated on the end slab 2 and in the offsets 41 a perfectly 90 tight joint is made all around.

95 While the construction and arrangement of the hog water fountain is that of a generally preferred form, obviously modifications and changes may be made without departing from the spirit of the invention or the scope of the claims.

I claim:

1. A fountain having a partition defining a water pan, a mud pan in said water pan providing an auxiliary bottom, means by which the mud pan may be lifted out including a bail, and means carried by the bail arranged to be moved into engagement with a portion of the adjacent partition to 105 lock the mud pan in place.

110 2. A fountain having a water trough, a partition dividing the trough into a float chamber and water pan, a mud pan in the water pan having a bail portion located close to the partition, a flap valve controlling the flow of water from the float chamber to the water pan, and a bulge formed in the partition on the float chamber side providing a chamber for the valve and ample 115 room for the operation thereof without interfering with the bail portion, said bulge having an opening.

120 3. A fountain having a water trough, a partition defining a water pan, a mud pan fitting in the bottom of the water pan to receive sediment, a bail attached to the mud pan by means of which it can be lifted out, a movable latch mounted on the bail and means including a flange affixed to the 125

partition to be engaged by the latch and thereby lock the mud pan in place.

4. A fountain comprising a container having upward side extensions provided with laterally aligning notches, a water trough seated in the container having upwardly extending means carrying flanges producing corners in registration with said notches,

and a cover for the water trough seated upon said flanges and having a peripheral 10 flange engaging the outside of the extension and fitting in the foregoing registering parts to produce a secure joint preventing the entrance of foreign matter into said trough.

MATHIAS J. HOSCH.
